MERCURY SWITCH

Nat Harris Freeman, La Mesa, Calif.

Application August 5, 1940, Serial No. 351,537
In Great Britain August 1, 1939

3 Claims. (Cl. 200—141)

This invention relates to temperature control devices of the kind wherein variations in temperature within a furnace or the like are communicated through an expansible fluid to a mercury operated switch adapted to open or close an electrical circuit arranged to actuate means for increasing or diminishing the furnace temperature and thereby restore such temperature to a predetermined level.

The object of the present invention is to provide improvements relating to the mercury switch in apparatus of the kind above indicated whereby certain disadvantages experienced in the working of such apparatus are avoided.

According to the present invention temperature control apparatus of the kind above described is provided wherein the operative parts of the mercury switch are at all times immersed in a liquid such as a hydrocarbon which will prevent oxidisation at the point of electrical contact.

Reference will now be made to the accompanying drawing which illustrates diagrammatically and by way of example a temperature control device constructed according to the invention.

In the device illustrated variations of temperature within a furnace chamber or the like are transmitted by means of a phial *a* containing an expansible fluid disposed within said chamber and communicating by means of a conduit *b* and passage *c* with one end of a tube *d* containing a body of mercury constituting one terminal of the electrical control circuit.

The passage *c* is formed through a plate *e* fixed to a supporting panel *f* and the tube *d* is fixed into a rotatable spigot *g* mounted in the plate *e*, the said spigot being hollow and having a port which maintains constant communication with the passage *c* in all positions of angular adjustment of the tube *d*, which adjustment is obtained by rotating a knob or hand wheel *h*.

Rotatable with the spigot *g* is a bracket *i* electrically insulated from the said spigot and plate *e*, the said bracket carrying the second terminal of the control circuit which consists of a rod or wire *j* which enters the end of the tube *d* remote from its mounting in the spigot *g*. The said rod or wire *j* is bent as shown to form a parallel portion *k* which is fixed in a carrier *l* movable along a guide rod *m* carried in a flanged portion *n* of the bracket *i*. Extending through the flange *n* and also engaging the carrier *l* is a screw threaded adjusting rod *o* which is held against axial movement so that as it is rotated the car-

rier *l* is caused to slide in either direction along the guide rod *m* and thereby adjust the position of the rod or wire *j* in relation to the surface of the mercury in the tube *d*. In this manner the rod or wire *j* can be set with exactness to the temperature at which the device is to become operative, that is to say when the temperature in the furnace chamber reaches a degree at which the mercury rises sufficiently within its tube and makes contact with the end of the rod or wire *j* and complete the electrical controlling circuit. This circuit includes wires *p* and *q* connected respectively to the plate *e* and to the flange *n* and which lead to a relay or other device by which the temperature control is effected.

For the purpose of preventing dust or other foreign matter from interfering with the operation of the device above described and to prevent arcing and corresponding oxidisation of the metal wire or rod *j*, the tube *d* is provided with a branch *r* for the attachment thereto of a flexible connection *s* leading to a reservoir *t* from which that portion of the tube *d* which is not occupied by the mercury is kept filled with a liquid hydrocarbon so that both contacts, mercury and the adjustable wire *j* are always immersed in such hydrocarbon. The outer end of the tube *d* has a closure element *u* which may conveniently be of a synthetic rubber material capable of making a fluid tight joint whilst permitting adjusting movement of the wire or rod *j*. As it has been found in practice that oxidisation can interfere to a serious extent with the correct functioning of the apparatus, the invention provides a simple and effective means of ensuring greater accuracy and a more strict control than has been possible hitherto, of the temperature within a furnace chamber or the like.

The conduit *b* communicates with a three-way connection *v* mounted on the plate *e*, and connected through a conduit *w* with a liquid seal *x* which constitutes a safety valve to allow gas or air under pressure to escape from the conduit *b* and prevent the mercury from being forced up the tube *d* by pressure instead of by heat conducted from the phial *a*.

I claim:

1. In a temperature control device, a supporting structure, an inclined tube carried by said structure and mounted for adjustment into a plurality of differently inclined positions, a conduit connected to said tube and containing a fluid expansible in response to variations in temperature, a body of mercury in said tube movable under the influence of said fluid, an electrical

contact element projecting into one end of said tube and engageable by the mercury, means for supporting said contact element exteriorly of the tube, for synchronous adjustment therewith, a side port in said tube, a flexible pipe connected to said port and extending upwardly, and a non-conductive liquid hydrocarbon contained in said tube over said mercury, said hydrocarbon being capable of preventing oxidation of said contact, and said pipe containing a body of said hydrocarbon and being operable to maintain a hydrostatic head on said hydrocarbon in said tube in all adjusted positions of the latter, and without interfering with tilting movement of said tube.

2. The temperature control device defined in claim 1, wherein said contact element is spaced from the walls of said tube and sealing means are provided between the latter and said contact element for preventing leakage of said hydrocarbon from said tube.

3. In a mercury switch device, a tube mounted at an inclination to the horizontal and containing mercury adapted to be raised and lowered by fluid pressure introduced adjacent the bottom of the tube, the latter having an open upper end, a contact element projecting into the open mouth of said tube and disposed substantially parallel to the axis thereof and adapted to be contacted by the mercury and close an electrical circuit, a liquid hydrocarbon disposed in said tube over the body of mercury, means supporting said contact element for longitudinal movement, for predetermining the height of mercury at which the circuit will be closed, and a closure member disposed in the mouth of said tube and sealingly associated with said contact element, and being operable to prevent egress of said hydrocarbon while permitting free adjustment of said contact element lengthwise of said tube.
